UNITED STATES PATENT OFFICE.

HARRY A. DRAKE, OF WEST NYACK, NEW YORK.

WOODEN BOAT OR DRAG.

Application filed December 17, 1925. Serial No. 76,049.

This invention relates to improvements in boats or drags such as are adapted for use in transporting stone, gravel and the like,—one object of the invention being to provide a boat or drag which shall be constructed of wood to the exclusion of metallic fastening means and employing no metal whatsoever with the exception of the drawbar or bars, and with the possible exception of the draw

10 pins.

With this object in view, the invention consists in certain novel features of construction and combinations of parts as hereinafter set forth and pointed out in the claims.

15 In the accompanying drawings,—

Figure 1 is a plan view of a boat or drag embodying my improvements.

Figure 2 is an end elevation section of the same.

20 Figure 3 is a side elevation.

Figure 4 is a view of one of the removable sideboards, and

Figure 5 is a view showing a modification.

25 Figs. 6 and 7 are enlarged detail sections.

My improved boat or drag comprises a plurality of floor planks 1, 2 and 3 or any other desired number of such planks and these planks are connected together by means of dowel pins 4 which enter sockets in edge

30 portions of the planks. At the sides of the floor structure, beveled wooden side beams 5 are placed upon the side portions of said floor structure and are secured thereto by wooden dowel pins 6 which extend, prefer-

35 ably in slanting directions through said side beams and the side floor planks. Each of these wooden pins is split at one end and the split portion receives a wedge 7 whereby it is securely clamped in place. The side beams

40 5 may also be provided with sockets 8 to receive pins 9 secured to and depending from sideboards 10 when said sideboards are used to increase the capacity of the boat or drag.

45 At respective ends of the boat or drag, a transverse wooden beam 13 is located upon the end portions of the floor structure and secured thereto by means of wooden pins 14 in the same manner as the side beams 5 are secured in place. The forward edge por-

tion of each transverse beam 13 is preferably 50 beveled as at 15. Centrally between the ends of each transverse beam 13, the same is provided in its under face with a recess 16 which receives a drawbar or link 17, the latter engaging at its inner end a draw-pin 55 18 of wood or other suitable material constructed in the same manner as the pins 6 and 14 and preferably disposed in an inclined position. The forward end of each draftbar or link 17 projects beyond the forward edge of the transverse beam 13 for connection with suitable draft means or the draftbar or link of another boat or drag.

When the boat is to be used as a single unit, the beam 13 might be displaced at one 60 end of the unit, by a cross-beam 11 secured upon the floor structure by means of wooden pins 12 constructed and employed in the same manner as are the pins 6.

Having fully described my invention what 70 I claim as new and desire to secure by Letters Patent, is:

1. A boat or drag comprising wooden floor members, transverse wooden beams at respective ends of said floor members, wooden 75 pins securing said transverse wooden beams in place, a draft pin carried by each of said wooden transverse beams, and draft links disposed loosely between the floor and the end beams and engaged around the respective draft pins.

2. A boat or drag consisting of the flat floor members arranged side by side, means engaged in opposed edges of the members to connect the members, the upper surfaces of 85 the members being entirely free of projections and the end edges of said members being beveled downwardly, end beams secured upon upper surfaces of floor members at the ends of the same, said beams having 90 longitudinally extending recesses in their undersides, draft links fitted freely in said recesses, and pins in the end beams engaged in said links.

In testimony whereof, I have signed this 95 specification.

HARRY A. DRAKE.
